CLAIM

The ornamental design for a taillight guard set for vehicles, as shown and described.

DESCRIPTION

FIG. 1 is a perspective view of the taillight guard set; FIG. 2 is another perspective view of the taillight guard set FIG. 1;

FIG. 3 is a front view of the taillight guard set seen in FIG. 1;

FIG. 4 is a rear view of the taillight guard set seen in FIG. 1;

FIG. 5 is a left side view of the left taillight guard of the taillight guard set seen in FIG. 1;

FIG. 6 is a right side view of the right taillight guard of the taillight guard set seen in FIG. 1;

FIG. 7 is a top view of the taillight guard set seen in FIG. 1; and,

FIG. 8 is a bottom side view of the taillight guard set seen in FIG. 1.

In the drawings, the broken lines depict portions of the taillight guard set that form no part of the claimed design. The dot-dash broken lines define the boundaries of the claimed design and form no part of the design. The claimed design is directed to the collective appearance of the parts of the taillight guard set, as shown. Where separate parts of the taillight guard set are shown in a single view, brackets are included to embrace the parts.
